David H. Wilson Inventor
By his Attorney H. D. Donnelly

UNITED STATES PATENT OFFICE.

DAVID H. WILSON, OF PHILADELPHIA, PENNSYLVANIA.

PHONOGRAPH-REPRODUCER.

1,390,963.

Specification of Letters Patent. Patented Sept. 13, 1921.

Application filed July 8, 1920. Serial No. 394,730.

To all whom it may concern:

Be it known that I, DAVID H. WILSON, a citizen of the United States of America, residing at 6031 Trinity street, in the county 5 of Philadelphia and State of Pennsylvania, have invented certain new and useful Improvements in Phonograph-Reproducers, of which the following is a specification.

This invention relates to phonographs, and 10 has special reference to reproducers for such instruments.

One important object of the invention is to improve and simplify the phonograph reproducer disclosed in my copending application 15 bearing the Serial No. 385,800 and filed on the 1st day of June, 1920.

A second important object of the invention is to effect the improvement above mentioned while retaining the characteristic spaced 20 point support for the sound box within the casing.

With the above and other objects in view, as will be hereinafter apparent, the invention consists in general of certain novel arrangements of details and combinations of parts hereinafter fully described, illustrated 25 in the accompanying drawings and specifically claimed.

In the accompanying drawings like characters of reference indicate like parts in the several views, and:—

Figure 1 is an enlarged perspective view of a reproducer constructed in accordance with this invention, the reproducer being cut 35 diametrically in half to show the interior thereof.

Fig. 2 is an enlarged detail section taken radially through one edge of the reproducer with the parts disassembled.

Fig. 3 is a view similar to Fig. 2 but with the parts assembled.

In the form of the invention herein illustrated, the same being typical of the various forms the invention may assume, there is 45 provided a plate 10 forming the back of the sound box and having its edges threaded. This plate is provided with a centrally disposed nipple 11 which projects rearwardly to fit over the neck 12 of a phonograph horn (the body of the latter not being shown). Screwed onto this plate is a ring 13 which is L-shaped in cross section and forms the side and front of the sound box, the central part of the latter being left open as shown 55 so as to expose the diaphragm 14 which is peripherally supported in the box by the hol-

low elastic rings 15 which are preferably formed of rubber tubing. These parts are so proportioned that, when assembled, the elastic rings are compressed as clearly shown 60 in Fig. 1.

Surrounding this sound box is a casing or housing consisting of a back member 16 having a centrally disposed opening 17 wherethrough the nipple 11 passes freely so 65 that the two do not contact. Projecting from the front face of this plate adjacent its periphery is an annular flange 18 threaded on its outer surface and fitting neatly around the ring 13 as shown. Screwed on the flange 70 18 is a ring 19 which is L-shaped in cross section so that the central part of the front of the housing is open.

In order to hold the casing or housing in position and yet have the same sufficiently 75 free from the sound box to prevent transmission of vibrations to the casing and thus interfere with proper tone production certain novel means are employed whereby the two parts are connected, or rather supported relative to each other, at spaced points. The means employed in the present instance consist of an annularly arranged series of projections here shown as set screws 20 threaded through the back member 16 and similarly 80 arranged and spaced projections such as the screws 21 threaded through the flange of the member 19, the screws of one series being axially aligned with the screws of the other series by preference. While here shown 85 as screws it is obvious that integral or other fixed projections may be used for this purpose. It will now be obvious that the sound box proper is supported within the casing by projections from that casing on opposite 90 sides of the sound box and at spaced intervals. Thus the sound box has great freedom 95 from the casing and may vibrate without such vibrations being damped by direct contact with such casing.

There has been provided a simple and efficient device of the kind described and for the purpose specified.

Having thus described the invention, what is claimed as new, is:—

1. In a phonograph reproducer, a sound box, a casing surrounding the back and front peripheral portions of the sound box, and spaced projections carried by and extending inwardly from the casing, said projections engaging the sound box at spaced 110 intervals adjacent its periphery.

2. In a phonograph reproducer, a sound box, a casing surrounding the back and front peripheral portions of the sound box, and annular series of spaced projections carried by the front and back portions of the casing and projecting inwardly from said casing, said projections engaging the sound box at spaced intervals adjacent its periphery.
3. In a phonograph reproducer, a sound box, a casing surrounding the back and front peripheral portions of the sound box, and annular series of spaced and adjustable projections carried by the front and back portions of the casing and projecting in-

wardly from said casing, said projections 15 engaging the sound box at spaced intervals adjacent its periphery.

4. In a phonograph reproducer, a sound box, a casing surrounding the front and back portions of the sound box adjacent its 20 periphery, and set screws projecting through the front and back portions of the casing and engaging the sound box at spaced intervals adjacent its periphery.

In testimony whereof I have hereunto 25 affixed my signature.

DAVID H. WILSON.
